UNITED STATES PATENT OFFICE.

CHARLES L. WECHT, OF LOGANSPORT, INDIANA.

SASH-FASTENER.

1,111,511.

Specification of Letters Patent. Patented Sept. 22, 1914.

Application filed April 4, 1914. Serial No. 829,512.

To all whom it may concern:

Be it known that I, CHARLES L. WECHT, a citizen of the United States, residing at Logansport, in the county of Cass and State 5 of Indiana, have invented certain new and useful Improvements in Sash-Fasteners, of which the following is a specification.

My invention relates to improvements in latches adapted to be used in connection 10 with window sashes, to hold or bolt them in open or closed positions.

An important object of the invention is to provide a device of the above-mentioned character which is simple in construction, 15 cheap to manufacture, and convenient in use.

A further object of the invention is to provide a device of the above-mentioned character, embodying a convertible bolt element, whereby the device may be secured to either 20 corner of the window, and employed to lock the same in place.

Other objects and advantages of the invention will be apparent during the course of the following description.

25 In the accompanying drawings forming a part of this specification, and in which like numerals are employed to designate like parts throughout the same,

Figure 1 is a side elevation of a latch embodying my invention showing the same in place. Fig. 2 is an end elevation of the same. Fig. 3 is a plan view of the same. Fig. 4 is a transverse section taken on line 4—4 of Fig. 3. Fig. 5 is a central longitudinal sectional view through the device. Fig. 35 6 is an enlarged perspective view of a combined latch plate and bolt, and Fig. 7 is a similar view of a track or base plate.

In the drawings wherein is illustrated a 40 preferred embodiment of my invention, the numerals 10 and 11 designate upper and lower sashes, mounted for vertical reciprocating movement in a frame embodying a vertical jamb or side 12, as shown.

45 The numeral 13 designates my device, as a whole, which is preferably secured to the upper end of the lower sash frame near either vertical edge thereof.

This device comprises a track or base plate 50 14, rigidly secured to the upper end of the lower sash frame, by means of screws 15' or the like, as shown. As clearly shown in Fig. 7, the base plate 14 is provided with longitudinally extending grooves 15 and 16, arranged upon the upper face thereof. The

grooves 15 and 16 forming upstanding longitudinal flanges or ribs 17 and 18 as shown.

Slidably mounted upon the base plate 14 to move longitudinally thereof, is a latch 60 plate 19, provided at its inner end with a lip or extension 20, as shown. Extending longitudinally of the latch plate and preferably formed integral therewith is a reciprocating bolt 21, having one end 22 formed preferably square in cross-section and the opposite end 23 formed circular in cross-section. A handle 24 is rigidly attached to the end portion 22, to move the same. The bolt and plate 19 are provided with a longitudinal slot 25, for a purpose to be described. The bolt 21 extends upwardly and downwardly beyond the opposite faces of the latch plate 19, forming in effect ribs to fit in the groove 15, (the plate 19 being invertible) 75 while the latch plate is provided with laterally extending longitudinal ribs or flanges '6 and 26' adapted to engage the outer edges of the ribs 17 and 18.

A cap-plate 27 is slidably mounted upon 80 the latch-plate 19, with a longitudinal groove 28, to receive the upper portion of the bolt 21, extending above the latch-plate. There are ribs or flanges 28' carried by the cap-plate to engage between the upper ribs 26 and 26', to hold said cap-plate against turning movement, as shown. A binding bolt 29 passes through a central opening in the cap-plate 27 and through the longitudinal slot 25 to have screw-threaded engagement in a central screw-threaded aperture 30, of the base plate 14, as shown. A spacing sleeve 31 is carried by the binding bolt 29, and is arranged between the cap-plate 27 and the base-plate 14, to prevent binding 90 action of the movable parts having slidable engagement with each other. 95

The latch plate 19 is provided near its outer end with an opening 32, to receive a lock pin 33, adapted to enter either of spaced 100 openings 34 formed in the base-plate, to lock the latch plate and bolt against movement.

Secured upon the vertical member of the upper sash frame are spaced superposed keepers 35 and 36 provided with horizontal grooves 37, to receive the lip or extension 20.

The vertical member jamb 12 is provided with openings to receive spaced superposed sleeves or bushings 38, disposed adjacent the 110 keepers 35 and 36. The sleeves 38 receive

the end 23 of the bolt 21, as is obvious. The upper end of the lower sash frame is provided with a vertical groove 39^a, for the passage of the keepers, as is obvious.

- 5 The operation of the device is as follows:—The lower sash may be moved to either closed or ventilating positions. This having been done, the bolt 21 is moved outwardly, whereby the end 23 thereof enters 10 socket 38, while lip 20 simultaneously moves into groove 37. It is thus seen that the upper sash is locked to the lower sash and the lower sash locked to the jamb or side of the frame. The pin 33 may be inserted in the 15 opening 34 to hold the latch plate and bolt against movement. The base plate 14 may be secured to either corner of the lower sash frame, and the lock-plate 19 may be inverted so that the bolt 21, will extend outwardly in 20 the proper direction to enter the socket 39, as is obvious. It is obvious that either set of ribs carried by the lock-plate are adapted to have detachable interlocking slidable engagement with the ribs of the base plate. 25 The cap-plate 27 is of course removable to permit of the inverting of the lock-plate.

It is to be understood that the forms of my invention are to be taken as preferred embodiments of the same, and that various 30 changes in the shape, size and arrangement of parts may be resorted to without departing from the spirit of the invention or scope of the subjoined claims.

Having described my invention what I 35 claim is:—

1. Apparatus to lock sash-frames together and one sash frame to the window frame; comprising a reciprocatory lock-plate; a bolt to engage with the window frame, formed 40 integral with the lock-plate, extending transversely thereof in spaced relation to the ends of the lock-plate, and having a longitudinal slot; means to secure the lock-plate to the

upper end of the lower sash-frame including an element passing through the longitudinal 45 slot; a second bolt secured to one end of the lock-plate in substantially parallel relation to the first-named bolt; and means carried by the upper sash frame, to engage the second bolt.

2. In apparatus of the character described, a guide plate adapted to be secured to one end of a sash frame and provided with a plurality of grooves, a lock plate provided upon its opposite sides with corresponding 55 ribs to enter the grooves of the guide plate whereby the lock plate may be inverted and having a longitudinally slotted bolt formed integral therewith and adapted to engage with the window-frame, a cap plate slidably engaging the upper surface of the lock plate and a bolt connecting the cap plate 60 and guide plate and passing through the longitudinal slot in the bolt.

3. In apparatus of the character described, a guide plate adapted to be secured to one end of a sash frame and provided with a plurality of grooves, a lock plate provided with depending ribs to be slidably mounted 65 within the grooves and having a longitudinally slotted bolt formed integral therewith and adapted to engage with the window frame, a cap plate slidably engaging the upper surface of the lock plate and a bolt connecting the cap plate and guide plate and 70 passing through the longitudinal slot in the bolt, and means to hold the lock plate in adjustment at a desired position with relation to the guide plate.

In testimony whereof I affix my signature in presence of two witnesses.

CHARLES L. WECHT.
